UNITED STATES PATENT OFFICE.

CHARLES F. RITCHEL, OF BRIDGEPORT, CONNECTICUT, ASSIGNOR TO THE
YANKEE MANUFACTURING COMPANY, OF SAME PLACE.

INK-WELL.

SPECIFICATION forming part of Letters Patent No. 632,588, dated September 5, 1899.

Application filed May 29, 1899. Serial No. 718,698. (No model.)

To all whom it may concern:

Be it known that I, CHARLES F. RITCHEL, a citizen of the United States of America, and a resident of Bridgeport, county of Fairfield, 5 State of Connecticut, have invented certain new and useful Improvements in Ink-Wells, of which the following is a specification.

My invention consists of improvements in ink wells or stands, whereby it is designed to 10 regulate the dip of the pens into the ink, so that the charge of ink will be graduated to the required amount and overcharge will be prevented and the charge will be clear and free of sediment. It is more particularly de- 15 signed for rapid hasty writers and children who have careless habits of dipping quickly and overloading the pen and especially to preventing clogging the pen with sediment from the bottom, all as hereinafter described, 20 reference being made to the accompanying drawings, in which—

Figure 1 is a sectional elevation of my improved ink-well. Fig. 2 is a top view. Fig. 3 is a horizontal section on the line 2 2 of Fig. 25 1; and Fig. 4 is a detail in vertical section on an enlarged scale, the section being taken on line 3 3, Figs. 1 and 3.

The well or stand *a* is a simple form of cup, preferably of glass, but may be of any approved material. It has a vertical interior groove *b*, or it may be a rib, and it also has a step-bearing recess *c* at the center of the bottom for the lower end of a vertical adjusting-screw *d*, and said well is provided with a cover 35 *e*, detachably connected in any way, as by a flange *f* and a spiral thread or threads *g*. An orifice *h* in the cover admits the pens for taking the ink. Over the cover is a rotating gate *i* to cover the orifice *h* when the ink-well 40 is not in use. This gate is attached to the upper end of the adjusting-screw *d* and serves as a finger-piece by which to turn the screw, the screw being pivoted in the center of the cover *e*, so as to turn freely. On the screw 45 is a vertically-adjustable pen-dipping controller *j*, consisting of a plate carried on the screw under the dipping-orifice *h* and having a guide-spur *k* running in the groove *b* to prevent it from turning with the screw. 50 The controller engages the threads of the screw in a way to be shifted up or down, according as the screw is turned one way or the

other, to graduate the position of the controller relatively to the level of the ink, it being intended to maintain the controller so far below the level as the depth to which it is desired to dip the pen for a proper charge of the ink, and thus while permitting the pen to be dipped to the extent required preventing it from dipping too deep. For the purpose of raising and lowering the controller it may be fitted on the screw by any suitable form of screw-threaded nut; but as a means of protection against jamming the nut against the bottom or the cover of the ink-well when 55 the nut has reached its limit of movements a nut of special contrivance adapted for automatic unclutching and reclutching with the threads of the screw is provided. The said nut consists in this example of the invention 60 of two elastic lips *l* of the controller-plate, which is made of thin springy metal, turned up from the edges of said plate and bent over so as to grip the screw between their edges, which being thin and taper “bite” into the 65 threads of the screw with ample pressure to cause the traverse of the controller along the screw until obstructed at the ends of the range, and then the lips will be wedged apart by the threads, which will then escape the 70 lips, while the screw may continue to be turned in the direction causing the controller to jam, but will continue their grip to shift the controller in the other direction when the screw is turned the other way. The lips *l* have 75 slight inclinations of their “biting” edges corresponding with the angular pitch of the threads of the screw for meshing with the threads accurately, the inclinations of the respective lips being in opposite directions because of the reverse inclinations of the threads 80 on the opposite sides of the screw. The hole *m* through the controller-plate below the lips for the screw forms a guide whereby the lips are prevented from escaping from the screw. 85

What I claim as my invention is—

1. The combination with an ink well or stand, of a controller for the dip of the pen in the ink, a screw for adjusting the controller relatively to the level of the ink, a cover 90 for the ink well or stand having an orifice admitting the pen subject to the controller, and a cover for said orifice, said cover being the finger-piece for operating the screw.

2. The combination with an ink well or stand, of a controller for the dip of the pen in the ink, an adjusting-screw whereon the controller is mounted and on which it travels 5 for adjustment relatively to the level of the ink, and a guideway and guide-stud for determining the traverse movements of the controller, said stud being on the controller and the guideway in the wall of the well.
- 10 3. The combination with an ink well or stand, of a controller for the dip of the pen in the ink, an adjusting-screw whereon the controller is mounted for adjustment relatively to the level of the ink, and an unclutching and clutching nut for releasing the controller at the ends of its traverse.
- 15 4. The combination with an ink well or stand, of a controller for the dip of the pen in the ink, an adjusting-screw whereon the controller is mounted for adjustment relatively to the level of the ink, and an unclutching and clutching nut for releasing the controller at the ends of its traverse, said nut consisting of the elastic lips of the controller gripping the opposite sides of the screw by 25 their edges.
5. The combination with an ink well or stand, of a controller for the dip of the pen in the ink, an adjusting-screw whereon the controller is mounted for adjustment relatively to the level of the ink, and an unclutching and clutching nut for releasing the controller at the ends of its traverse, said nut consisting of the elastic lips of the controller gripping the opposite sides of the screw by 30 35 their edges, the controller-plate having an orifice for the screw forming a guide.

Signed by me at New York, N. Y., this 25th day of March, 1899.

CHARLES F. RITCHEL.
